ROTARY SURFACING TOOL

Robert K. Taylor, Spartanburg, S. C.

Application March 7, 1938, Serial No. 194,443

4 Claims. (Cl. 90—12.5)

This invention relates to surfacing tools for refinishing triple valve seats or any other device wherein the valve seat face may become uneven from wear or any other cause and has for the primary object the provision of a device of this character which employs a power driven rotary cutter and a holder therefor, whereby the device may be manually moved over a seat to re-finish the latter and thereby remove irregularities therefrom, the holder and power drive being of such a construction that adjustment may be easily and quickly made to vary the depth of the cut made by the cutter.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a rotary surfacing tool constructed in accordance with my invention.

Figure 2 is a top plan view illustrating the device.

Figure 3 is a transverse sectional view showing the tool in engagement with a valve seat of the type employed in a triple valve.

Figure 4 is a fragmentary longitudinal sectional view showing a portion of the holder and the power driven cutter carried thereby.

Figure 5 is a detail side elevation showing a part of the power drive means.

Figure 6 is a fragmentary bottom plan view showing the cutter.

Referring in detail to the drawing, the numeral 1 indicates an elongated body of a holder having connected to one end a handle 2 and its opposite end a control valve 3. The body intermediate its ends is provided with an opening 4 to receive a fluid motor 5. The walls of the opening 4 are chambered to form an annular passage 6 and in direct communication therewith is a passage 7 to which the valve 3 is connected. Through the use of a flexible hose or pipe 8 the valve 3 is connected to a source (not shown) of fluid pressure.

The walls of the opening 4 are screw threaded 50 to match screw threads of a cylinder 10' forming a part of the fluid motor. The cylinder has ports 11' in direct communication with the passage 6. The cylinder 10' extends through the top wall of the body 1 and has threaded thereon a cap 12 having exhaust ports 13 and also integral there-

with is a bearing 14 rotatably supporting the shaft 15. The shaft 15 is further rotatably supported by an end wall of the cylinder 10' and has threaded thereon the cutter 16. Secured on the shaft 15 is a plurality of blades 17 so arranged with respect to the ports 11 that the fluid pressure may impinge against said blades for the rotation of the shaft 15 and the cutter carried by the latter. The fluid pressure escapes from the cylinder 10' by way of the exhaust ports 13. The cylinder 10' being threaded in the body permits the cutter to be adjusted relative to the work engaging face A of the body. Detachably secured on the body to provide said face are wear plates 11' and 12' which are slightly wider than the body and thereby forming guide flanges 18 and 19, respectively. In use, the end B of the body is the advance end and the end C the trailing end. The plate 12' carrying the flanges 19 is of a greater height than the plate 11' carrying the flanges 18, the plate 11' being disposed next to the advance end B of the body while the plate 12' is disposed next to the trailing end C of the body. In other words, the plate 11' travels in advance of the cutter while the plate 12' trails the cutter. The cutter is adjusted so as to cut a selected distance below the bottom face of the plate 11'. Consequently, the thickness of the plate 11' governs the depth of the cut while the plate 12' rides on the refinishing surface maintaining the body throughout its length level and fully supported on the device being resurfaced. By having the wear plates detachably mounted on the body 1 the operator may remove said plates and substitute others of different dimensions when desiring to vary the cutting action of this tool. When the plates are changed the rotary cutter also is accordingly adjusted or removed and substituted by another of a different cutting capacity.

The device described in detail and shown in the drawing is especially adapted for resurfacing or refinishing a valve seat 20 of a triple valve. The valve seat in this instance forms an integral part of a sleeve 21 so that in order to refinish the valve seat it is necessary to move the tool endwise through the sleeve 21. This operation is clearly shown in Figure 3. As the tool is advanced, with the motor in operation, endwise of the sleeve 21 and against the valve seat, the cutter 16 refinishes the valve seat removing therefrom all irregularities caused by wear and other causes. During the use of this tool the operator grasps the handle 2 and the valve 3 for the manipulation of the body 1 relative to the valve

seat, consequently it will be seen that the tool described is convenient to handle and move relative to a valve seat and will efficiently re-finish the valve seat with maximum accuracy.

5. What is claimed is:

1. A surfacing tool comprising an elongated body having an opening therethrough and a passage in communication with said opening and extending through one end of said body, means for

10 connecting said passage to a fluid supply, a fluid motor adjustably mounted in said opening and in communication with the passage to be driven by fluid pressure, and a rotary cutter secured to said motor and adjustable relative to one face of the body.

15 2. A surfacing tool comprising an elongated body having an opening therethrough and a passage in communication with said opening and extending through one end of said body, means for

20 connecting said passage to a fluid supply, a fluid motor adjustably mounted in said opening and in communication with the passage to be driven by fluid pressure, a rotary cutter secured to said motor and adjustable relative to one

25 face of the body, and guides on said face of the body for guiding the movement of the body over a surface and for gaging the depth of the cut made by said cutter.

30 3. A surfacing tool comprising an elongated body having a screw threaded opening and a passage in communication with said opening, a valved means for connecting said passage to a fluid pressure supply, a cylinder threaded in

said opening and having ports in communication with the passage, a cap threaded on said cylinder and engaging one face of said body and provided with exhaust ports, a shaft rotatably supported by said cylinder and the cap, blades secured on said shaft and arranged adjacent the first named ports to be acted on by fluid pressure, and a rotary cutter secured to said shaft and adjustable relative to another face of said body by the rotation of the cylinder in the body in opposite directions.

5 4. A surfacing tool comprising an elongated body having a screw threaded opening and a passage in communication with said opening, a valved means for connecting said passage to a fluid pressure supply, a cylinder threaded in said opening and having ports in communication with the passage, a cap threaded on said cylinder and engaging one face of said body and provided with exhaust ports, a shaft rotatably supported by said cylinder and the cap, blades secured on said shaft and arranged adjacent the first-named ports to be acted on by fluid pressure, a rotary cutter secured to said shaft and adjustable relative to another face of said body by the rotation of the cylinder in the body in opposite directions, and guides formed on the last-named face of the body, certain of said guides acting to gage the depth of cut made by said cutter and the other guides aiding in supporting the body for movement over a surface.

ROBERT K. TAYLOR.
